UNITED STATES PATENT OFFICE.

JULES ROYDET DESJARDINS, OF BURLINGTON, VERMONT.

WINDMILL.

SPECIFICATION forming part of Letters Patent No. 339,977, dated April 13, 1886.

Application filed August 19, 1884. Serial No. 140,939. (No model.)

To all whom it may concern:

Be it known that I, JULES ROYDET DESJARDINS, of Burlington, in the county of Chittenden and State of Vermont, have invented 5 new and useful Improvements in Windmills, of which the following is a full, clear, and exact description.

My improvements relate to windmills of the type shown in Letters Patent granted to 10 me May 27, 1879, No. 215,892.

The object of the invention is to provide a wheel of substantial and durable character that can be adjusted to the force of the wind and according to the power required, and 15 when not in use can be arranged so that the fans offer no resistance to the wind.

A further object is to provide for checking the speed of the wheel automatically when the wind-pressure becomes excessive.

20 To these ends my invention consists in novel mechanism for adjusting the stops that regulate the position of the hinged fans or sails.

It consists, also, in brake mechanism fitted 25 for operation by an independent vane for regulating the speed of the wheel; also in the construction of the tower for supporting the wheel, and in certain details of construction and arrangement, all as hereinafter described and claimed.

30 Reference is to be had to the accompanying drawings, forming part of this specification, in which similar letters of reference indicate corresponding parts in all the figures.

Figure 1 is a front elevation of the wheel 35 and stand. Fig. 2 is a vertical section in the plane of the axis. Fig. 3 is a face view of the wheel with certain parts modified. Fig. 4 is a side view, partly sectional, of the wheel as mounted on a tower. Figs. 5 and 6 show 40 modifications in the construction of the wheel.

The wheel is to be mounted either upon a portable frame, as shown in Figs. 1 and 2, or upon a tower, as shown in Fig. 4, when located permanently.

45 The shaft A of the wheel is supported upon the upper cross-timbers, a, of the frame or tower, and the wheel is at the mid-length of the shaft, so as to rotate between the timbers a.

50 The construction of the wheel is as follows: The hub b has spokes or arms, carrying a

ring, c, and from the ring c radiate the arms d, that carry the fans or sails e. On the ends of arms d are flanged heads f, and the heads of the several arms are connected by tie-rods 55 g, which are secured by nuts on their ends, so that they can be drawn tightly. This construction allows looseness at any one arm to be taken up. The fans are hung to arms d by hinges h at one edge, as shown in Fig. 1, or 60 the hinges may be on the ends of the fans, as shown in Fig. 3, a short distance from the side, so that the fan projects at both sides of the arm, the projection at one side being about twice the width of the portion at the 65 other side. The hinges h are of strap form, and are riveted to the fans at their opposite sides alternately.

The inclination of the fans by pressure of the wind is regulated by stops i, which are 70 shown in Fig. 1 as carried by eyes k, attached to ring c and to an inner ring, l, carried by the hub-spokes, whereby the stops are held in radial positions and are free to move endwise. They are held in their outward position by their inner ends resting on a ring, m, and in that position the outer ends of the stops are in front of projections n on the fans, so as to prevent the fans from opening, except to a limited extent. The ring m is sustained on 75 pins o, projecting from ring l, and the pins carry spiral springs p, that retain ring m outward. When the ring m is pressed inward, the stops i can be moved toward the center of the wheel, thereby freeing their outer ends 80 from the projections n on the fans, and the stops are held in this position by heads or lugs on their ends taking upon the inner surface of ring m. Upon pressing the ring m inward the heads of the pins will be disengaged therefrom, and as the wheel slowly revolves said pins will by their own weight be returned to 85 their normal position. The ring will of course be thrown outward by its springs to its position beneath the lower heads of the pins i. 90

In Fig. 3 the stops i are pivoted to ring c, so as to swing in and out of contact with projections n on the fans, and their inner ends are connected to ring l by screws passing through slots in the stops. There are two rings l, 100 held to opposite sides of the spokes by connecting-bolts from one ring to the other, and

the spokes have lugs holding the rings in place and allowing them to turn partly around. A lever, q , (see Figs. 1, 2, 3, and 4,) is connected to one ring l , for use in moving the rings to swing all the stops at once, and the lever engages a rack, q' , attached to ring c , so as to prevent accidental movement.

It is to be understood that as the fans swing both ways, according to the direction of the wind, the stops and other parts are placed on both sides of the wheel.

Upon one end of the wheel-shaft is a crank-wheel, r , to which a pitman may be connected, and the wheel is grooved for a wire rope when the power is to be conveyed in that manner. On the opposite end of the shaft is a larger wheel, s , having a V-grooved rim for a wire rope and beveled edges, and this wheel is provided with a side flange or rim, t , for connection of a belt.

Upon the frame, beneath wheel s , are hung two levers, u , that carry at their upper ends brake-shoes v , shaped to clasp the beveled edges of wheel s , and the lower ends of the levers are connected by bars w , which are jointed together so as to form toggle-bars. a' is a lever, hung on the frame and extending over the toggles w , and also connected to the toggles. On this lever is a sliding weight, b' , which bears down the lever and toggles, so as to release the brake-shoes from wheel s . A rod, c' , from the outer end of lever a' , extends upward and connects to the arm of a vane, d' , that is hung on a post, e' , so as to swing in a vertical plane. In the normal position of the vane it is held nearly upright by the weight on lever a' until the wind-pressure is sufficient to overcome the weight and press the vane toward a horizontal position. This movement of the vane raises the lever and presses the brakes against wheel s with more or less force, thereby checking the speed of the wheel.

When the wind-pressure decreases, the vane rises and relieves the brake, and by these combined movements the wheel is regulated to run at any desired speed.

I prefer to apply a weight to the toggles w , as shown, for relieving the brakes from the wheel.

To hold the brake in contact when the wheel is not in use, I provide a pin, f' , on post e' in position to support the end of lever a' when the latter is raised. When the wheel is mounted in a tower or a building, there may be a rope connected to the brake-lever and passing over a pulley and down into the building for use in applying the brakes.

As shown in Fig. 4, I provide a tower constructed specially in its upper portion for use with the wheel. On account of there being cross timbers or plates a on two sides of the tower the corner-posts h' of the tower are braced by struts g' , extending from the cross-timbers i' of the platform, so as to resist any tendency of the posts h' to spread and insuring rigidity. The wheel may also be mounted

ed on two posts having braces extending to the ground.

The fans, wheel-center, arms, and other parts may be made of wood or other material. When the wheel is made with a wooden center, the construction is as shown in Fig. 5. The ring a' is formed of wood clamped between iron plates, and the arms or standards d , which are made of tubing, passing through the wooden ring have clamping-nuts b' at the inner and outer surfaces of the ring, so that the arms are held perfectly rigid.

Fig. 6 shows the brake-pulley s made of wood in the same manner. The wooden spokes are clamped between flanges on the two hub-pieces that are held together by cross-bolts.

Having thus described my invention, what I claim as new, and desire to secure by Letters Patent, is—

1. The combination, in a wind-wheel, with the hinged fans, of vertically-sliding stops at opposite sides thereof, laterally-moving rings m below the lower ends of said pins, horizontal pins supporting said rings, and spring p on the pins for pressing the rings outward, substantially as set forth.

2. The combination, in a wind-wheel, of the hinged fans e , the ring c , to which said fans are hinged, the inner rotatable rings, l , within the ring c , and connected by cross-bars, the stops i , movably connected with the rings c and l at or near their lower and middle portions, the lever q , secured to one ring l , and the rack q' , secured to the ring c and adapted to engage the free end of said lever, the upper ends of the stops i extending on opposite sides of the lower ends of the said fans, substantially as set forth.

3. The combination, in a wind-wheel, of the vertical hinged fans, the fixed ring to which they are secured, and the inner rotatable rings, eyes on said inner and outer rings, headed pins held by said eyes, and the upper ends of the pins extending on opposite sides of the said fans, substantially as set forth.

4. The combination, in a wind-wheel, of the outer ring, c , the hinged fans e , the inner rotatable rings, l , and means for operating them, with the vertically-sliding pins connected to the rings l and c , and the laterally-adjustable rings m , on the peripheries of which the inner ends of the pins rest, the horizontal pins o , on which said rings m are mounted, and the springs p for pressing the rings m outward, substantially as set forth.

5. The combination, with a wind-wheel and its shaft, of brake-wheel s , having beveled edges and V-grooved rim, and the levers u , carrying brake-shoes v , substantially as described.

6. The combination, with a wind-wheel and its shaft, of brake-wheel s , brake-levers u , toggle-bars w , and lever a' , substantially as described, for operation as specified.

7. The combination, with a wind-wheel, its shaft and a brake-wheel thereon, of a brake-

shoe, a weighted lever connected with said shoe forcing it away from said brake-wheel, a vertically-swinging vane, and a rod connecting the vane and lever below the pivoted point 5 of the latter, whereby when the lever assumes a horizontal position it will raise the lever and engage the brake-shoe with the brake-wheel,

and when the vane is vertical the weighted lever will withdraw the brake-shoe from the brake-wheel, substantially as set forth.
